ROCKING HORSE

Emanuel Pressner, South Orange, N.J., assignor to Banner
Plastics Corporation, Paterson, N.J., a corporation of
New York

Application March 27, 1959, Serial No. 55,215

Term of patent 14 years

(Cl. D34—15)

FIG. 1

Fig. 1 is a perspective view of a rocking horse according to the invention;

Fig. 2 is a front view of the rocking horse shown in Fig. 1; and

Fig. 3 is a rear view of the rocking horse shown in Fig. 1.

I claim:

The ornamental design for a rocking horse, as shown.
